UNITED STATES PATENT OFFICE

2,645,928

BUILDING CONSTRUCTION

Charles J. Roos, Muskegon, Mich.

Application November 3, 1949, Serial No. 125,185

1 Claim. (Cl. 72—33)

1

This invention relates to a building structure and method of producing the same, the primary object of the invention being to provide a structure which may be erected without the use of staging or sway plumb, holding devices or the like.

An object of the invention is to provide a wall structure which during the erection of the wall, utilizes the hardened concrete of the previous layers of poured concrete for steadyng and maintaining the wall in the perpendicular.

Another object of the invention is the provision of a wall construction wherein the adjacent upper and lower ends of forms will be secured together by their overlapping relation, together with securing members extended through the overlapped portions of the forms.

Another object of the invention is to provide a structure wherein inferior lumber may be utilized in the construction of the forms which become sleepers in the finished wall construction, thereby eliminating the necessity of using high grade lumber in the wall construction, thereby reducing the cost of wall construction to a minimum.

With the foregoing and other objects in view which will appear as the description proceeds, the invention consists of certain novel details of construction and combinations of parts, herein-after more fully described and pointed out in the claim, it being understood that changes may be made in the construction and arrangement of parts without departing from the spirit of the invention as claimed.

Referring to the drawings:

Figure 1 is a vertical sectional view through a wall constructed in accordance with the present invention.

Fig. 2 is a perspective view illustrating a standard window provided with anchor wires and used in conjunction with the wall construction.

Fig. 3 is a perspective view taken from the rear of a form board constructed in accordance with the invention.

Fig. 4 is a perspective view illustrating a form board constructed of clear slats from high grade lumber to be retained as a part of the finished wall construction.

Fig. 5 is a vertical sectional view illustrating the bottom forms of a wall construction filled with concrete with adjacent upper forms positioned thereon.

Fig. 6 is a vertical sectional view through the lowermost section of the wall illustrating a slat positioned vertically with a wedging means for

2

aligning the upper edges of the adjacent upper forms.

Fig. 7 is a perspective view of a bracket used in supporting the upper forms during the building of the wall.

Referring to the drawings in detail, the reference character 5 indicates the foundation on which the wall forming the essence of the present invention, is erected.

10 In forming the wall I use forms 6 and 7, the forms 6 which constitute the inner forms of the wall structure, being constructed of slats 8, of inferior wood, that is, wood which is knotty and has rough and irregular surfaces. These slats are connected by transversely extended cleats 9 that have beveled side edges, the cleats being spaced apart predetermined distances so that when they become embedded in the concrete poured between the forms used in the construction of the wall, these cleats will constitute sleepers.

20 The form 7 which is the outer form used in the wall construction, is made up of a plurality of slats 10, which have their adjacent edges in contact, since these slats 10 provide the outer surface of the wall when completed.

25 The slats 10 are connected by means of the cleats 11 that are secured to the inner surfaces of the slats by means of the nails 12, the cleats 11 also having their side edges beveled so that the concrete or plastic material may anchor itself around the cleats.

30 In constructing a wall in accordance with the present invention, the inner and outer forms 6 and 7 are arranged to provide the lowermost or first section of the wall, the lower ends of the forms being wider apart than the upper ends, thereby providing inclined wall surfaces. These forms are used in building the wall, and after the concrete indicated at 13 has been poured between the forms of the lowermost section of the wall, the forms of the adjacent upper section are positioned with their lower ends overlapping the upper ends of the adjacent lower forms at 14.

35 Nails 15 are now driven through the lower overlapped ends of the upper form and through the upper ends of the lower forms, the nails passing into the cleats 9 and 11 of the inner and outer forms, respectively. Thus it will be seen that the upper forms are firmly secured, and this operation is continued throughout the building of the wall. It will, of course, be understood that with the positioning of each set of forms, the space between the forms will be filled with concrete, which when allowed to set, will firmly an-

chor the forms to the concrete, providing an exceptionally rigid construction, and at the same time provide a finished wall surface.

In order that the tapered construction of the sections of the wall formed by the present method, may be carried out spacing bars 16 are provided, the spacing bars having cleats 17 secured to the under surface thereof, the space between the cleats 17 of each bar being equal to the width of the upper end of each wall section being constructed. The cleats 17 as shown, rest against the uppermost slats of the inner and outer forms, holding them against spreading during the pouring of the concrete between the forms. Nails 18 are driven through the spacing bars 16 and pass into the uppermost slats of the forms, temporarily securing the spacing bars in position on the forms, to be removed when the concrete between the forms has properly set.

In order that the forms may be further braced against downward movement, brackets 19 are provided, the brackets 19 being secured to the outer surface of the outer form in the construction of each wall section, so that the lower end of the adjacent upper and outer section may rest therein. Removable nails 20 are used in securing these brackets in position.

As shown by Fig. 2 of the drawings, the window frame 21 which is of suitable construction, is provided with rods 22 that connect the strips 23 and provide anchoring means around which the concrete poured in the wall construction, anchors it self. It might be further stated that the strips 23 of the window sash fit between the ends of the outer and inner forms of the sections of the wall to firmly secure the window sashes in position.

In erecting the wall I use a gauge bar 24 which is secured to the inner form of the lowermost section by means of nails 25. The guide bar is now arranged so that it will stand perpendicular. The wedge 26 is now moved between the gauge bar 24 and outer edge of the inner form of the adjacent upper section and nailed in such position by

means of nails 27, to maintain the gauge bar 24 in this perpendicular position, and prevent the spreading of the forms in building the sections to cause the sections to be erected out of alignment.

Reinforcing rods 28 are embedded in the concrete, in the usual and well known manner.

From the foregoing it will be seen that due to the construction shown and described, I have provided a wall construction which may be built up in sections without the use of ties or spreaders at the bottoms of superimposed sections, the fastening of the forms of one section permanently to the forms of the adjacent lower section, eliminating the use of such ties and spreaders.

Having thus described the invention, what is claimed is:

A building construction embodying superposed sections, each section comprising spaced outer and inner forms inclined inwardly towards the upper edge of such section providing sections having wide lower edges and narrow upper edges vertical cleats secured to the inner surfaces of the forms with their upper and lower ends spaced from the upper and lower ends respectively of the sections, the lower wide edge of one section being fitted over the narrow upper edge of the adjacent lower section, and securing nails extending through the forms of adjacent sections, securing the sections together.

CHARLES J. ROOS.
